UNITED STATES PATENT OFFICE

JÖRGEN F. H. FECHTBURG, OF CHELTENHAM TOWNSHIP, MONTGOMERY COUNTY, PENNSYLVANIA

SUCTION COMB

Application filed November 20, 1928. Serial No. 320,607.

This invention relates to what may be termed a suction comb and is particularly adapted for use in the cleaning of cows, horses and other animals. The device comprises a comb which is adapted to sleek the animal's coat and at the same time loosen any dirt or scurf which may be imbedded in the hair, the suction nozzle, which is combined with the comb, acting to carry the foreign matter away immediately and thereby prevent its resettling on the animal.

It will be understood that the suction nozzle is adapted to be coupled to any suitable form of vacuum producing apparatus for creating the desired suction in the nozzle around the comb.

One object of the invention is to construct the comb in such a manner that loose hair will not become entangled in the comb and thereby clog the nozzle.

Another object of the invention is to form the nozzle in two separate pieces, comprising the nozzle proper and a hollow or tubular handle therefor, and so constructing these elements that the nozzle proper, which is of wide expanse and is adapted for use in cleaning the readily accessible parts of the animal, may be quickly removed from the hollow handle which on its end is provided with comb teeth and is adapted to be used alone in cleaning those parts of the animal which are not so readily accessible.

Referring to the drawings:

Fig. 1 is a longitudinal sectional elevation of the device taken on the line 1—1, Fig. 2;

Fig. 2 is a transverse sectional elevation taken on the line 2—2, Fig. 1;

Fig. 3 is an inverted plan view;

Fig. 4 is an end view of the tubular handle of the device; and

Figs. 5, 6, 7 and 8 illustrate alternate forms of the invention.

The device comprises a suction nozzle 1, which consists of an elongated substantially flat hollow body portion 2 which gradually increases in height from its opposite ends toward its center where the said hollow body portion is provided with a substantially cylindrical hollow extension 3, which projects from one side of the said body portion at an

angle with respect to the general plane of the said body portion.

The respective side walls 4 and 5 of the hollow body portion 1 are spaced apart to form an elongated mouth or opening 6 in which is located the comb 7.

The comb 7 comprises a solid portion or back 8 which is located within the opening 6 of the body portion 2 and is spaced above and substantially parallel to the bottom edge 9 of the said body portion 2. Teeth 10 of the comb project from the back 8 of the comb to a point below or outside the bottom edge 9 of the body portion 2 of the suction nozzle 1.

The comb 7 may be applied to the nozzle by slotting the end walls 11, 11 of the body portion 2 as at 12 and placing the ends of the comb in said slots, swaging the ends of the comb over the said end walls 11 at each side of the slots, or by sweating, soldering, or welding the comb in the slots, or by locating the comb in a suitable die and casting the body portion 2 around the comb to hold the comb in place.

The metal at the base of spaces formed between adjacent teeth 10 is beveled in both directions from the central plane of the comb as indicated at 13 presenting a knife edge to the dirt and hair being drawn into the nozzle 1.

I have found by experimentation that this construction prevents loose hairs from piling up between the teeth and clogging the nozzle, the knife edge 14 preventing the hairs from balancing on the comb with one end on one side thereof and the other end on the opposite side thereof, such as happens when the base of the spaces between the teeth are permitted to remain flat and at right angles to the direction of travel of the air moving into the nozzle.

Obviously for short haired animals the teeth 10 do not extend as far below the bottom edge 9 of the nozzle as is the case where the comb is to be used on long haired animals. Likewise the spacing of the teeth may vary in accordance with the state of compactness of the hair on different animals.

The inner face of the wall of the extension 3

is slightly tapered to receive the externally tapered end 15 of a suitable hollow handle 16, which is adapted to be connected in any suitable manner to a flexible hose or other conduit extending from the vacuum apparatus, not shown.

The end of the hollow handle 16 lying within the extension 3 is provided with a series of spaced teeth 17 as illustrated in Figs. 1 10 and 4.

For ordinary use on the readily accessible parts of the animal the nozzle 1 is employed, being frictionally held on the hollow handle 16 but for the places less accessible, such for 15 example as the places where the limbs join the body, the nozzle 1 may be removed and the toothed end of the hollow handle employed to comb and clean in such places, in which case the hollow handle functions as 20 the nozzle.

Placing the comb directly in the center of the nozzle mouth, or opening 6 and running the comb longitudinally of the opening with the walls 4 and 5 spaced relatively close to 25 the comb on each side thereof permits the dirt to be loosened by the comb and immediately removed from the hair and does not allow the dirt to settle on another part of the animal's body.

30 Spacing the knife edges 14 inwardly from the bottom edge 9 of the nozzle permits the teeth to thoroughly comb the hair without the hair becoming entangled in the teeth by the suction in the nozzle.

35 If desired, the comb may be removably secured in the nozzle 1 in any suitable manner, such for example as that illustrated in Fig. 5, wherein the ends of the comb 7a extend beyond the end walls 11, 11 as illustrated at 40 18, and a pin or other securing device 19 passed through the ends 18 of the combs resting in sockets 20 formed at the intersection of the bead 21, which is formed around the mouth of the nozzle, with the body portion 45 of the nozzle.

By making the combs removable, combs having various degrees of coarseness, or teeth of various lengths, etc., may be readily placed in the nozzle to meet the requirements of various existent conditions.

In Fig. 6, I have shown a comb 7b in which the teeth are curved outwardly, in a direction away from the handle of the nozzle, as illustrated at 10b, the portion of the teeth extending beyond the plane $\alpha-\alpha$ of the mouth of the nozzle being disposed substantially at an angle relative to the plane of the mouth of the nozzle. This curvature of the teeth obviates the possibilities of the teeth pressing 55 into the hide when the device is pushed rather than pulled over the hide. In pushing the device over the hide, the curvature of the teeth 10b presents the lower portion of the teeth at an acute angle with respect to the hide whereupon the teeth will readily ride

over the hide rather than having a tendency to dig into the hide. In pulling the device over the hide the natural tendency is for the teeth to move away from the hide, therefore, there is no tendency for the teeth to dig into the hide. The operation of this form of the device is smooth and efficient even in the hands of the most inexperienced or indiscreet operator.

Obviously the curvature of the teeth 10b 7 may be eliminated and the portion of the teeth extending beyond the plane $\alpha-\alpha$ of the mouth of the nozzle bent at an angle other than ninety degrees with respect to said plane as shown at 10c Fig. 7, with equal effectiveness.

In Figs. 7 and 8, I have shown a comb adapted especially for use with animals which are shedding hair. In this form of the invention the teeth of the comb are spaced 8 relatively far apart and the bases of the spaces between the teeth are curved as at 20, thereby presenting no sharp corners in which loose hair may collect. Also these bases are beveled on one side only as indicated at 13c, 9 and these bases are located but a slight distance from the plane $\alpha-\alpha$ of the mouth of the nozzle, so that should any loose hairs become entangled in the teeth of the comb they may be readily removed by merely removing the nozzle 1 from the handle 16 and running the end of the handle across the comb, the suction in the handle 16 thereby removing the loose hairs from the teeth of the comb.

I claim:

1. The combination of a suction nozzle having a hollow body portion terminating in an elongated mouth opening of restricted width and wherein opposite sides of said mouth opening are defined by a pair of relatively spaced rectilinear walls extending in planes substantially parallel to each other with the edges of said walls at the mouth opening unbroken and disposed in a common plane substantially at right angles to the planes of said walls, and a comb disposed in said mouth opening in a plane intermediate and in substantially parallel spaced relation to each of said side walls, providing an unobstructed relatively narrow air passage extending from said mouth opening into the said hollow body portion of the nozzle at each side of the comb between the comb and the adjacent side wall of the nozzle whereby the suction will be concentrated at each side of the comb.

2. The combination of a suction nozzle having a hollow body portion terminating in an elongated mouth opening of restricted width and wherein opposite sides of said mouth opening are defined by a pair of relatively spaced rectilinear walls extending in planes substantially parallel to each other with the edges of said walls at the mouth opening un-

broken and disposed in a common plane substantially at right angles to the planes of said walls, and a comb disposed in said mouth opening in a plane intermediate and in substantially parallel spaced relation to each of 5 said side walls, providing an unobstructed relatively narrow air passage extending from said mouth opening into the said hollow body portion of the nozzle at each side of the comb between the comb and the adjacent side wall 10 of the nozzle whereby the suction will be concentrated at each side of the comb, said comb comprising spaced teeth projecting outward beyond the plane of the mouth opening and the bases of the spaces between the teeth being located within the mouth of the nozzle and spaced inwardly from the said plane of the mouth opening. 15

3. The combination of a suction nozzle 20 having a hollow body portion terminating in an elongated mouth opening of restricted width and wherein opposite sides of said mouth opening are defined by a pair of relatively spaced rectilinear walls extending in 25 planes substantially parallel to each other with the edges of said walls at the mouth opening unbroken and disposed in a common plane substantially at right angles to the planes of said walls, and a comb disposed 30 in said mouth opening in a plane intermediate and in substantially parallel spaced relation to each of said side walls, providing an unobstructed relatively narrow air passage 35 extending from said mouth opening into the said hollow body portion of the nozzle at each side of the comb between the comb and the adjacent side wall of the nozzle whereby the suction will be concentrated at each side of the comb, said comb comprising 40 spaced teeth projecting outward beyond the plane of the mouth opening and the bases of the spaces between the teeth being located within the mouth of the nozzle in a plane substantially parallel to and spaced inwardly 45 from the plane of the mouth of the nozzle.

4. The combination of a suction nozzle having an elongated mouth opening of restricted width and wherein opposite sides of said mouth opening are defined by a pair of relatively spaced rectilinear walls extending in 50 planes substantially parallel to each other with the edges of said walls at the mouth opening unbroken and disposed in a common plane substantially at right angles to the planes of said walls, and a comb disposed 55 in said mouth opening in a plane intermediate and in substantially parallel spaced relation to each of said side walls, providing an unobstructed relatively narrow air passage 60 at each side of the comb between the comb and the adjacent side wall of the nozzle whereby the suction will be concentrated at each side of the comb, said comb comprising spaced teeth projecting outward beyond the 65 plane of the mouth opening and the bases of

the spaces between the teeth being located within the mouth of the nozzle and spaced inwardly from the said plane of the mouth opening, the said bases being beveled toward the mouth of the nozzle. 70

5. The combination of a suction nozzle having an elongated mouth opening of restricted width and wherein opposite sides of said mouth opening are defined by a pair of relatively spaced rectilinear walls extending in 75 planes substantially parallel to each other with the edges of said walls at the mouth opening unbroken and disposed in a common plane substantially at right angles to the planes of said walls, and a comb disposed 80 in said mouth opening in a plane intermediate and in substantially parallel spaced relation to each of said side walls, providing an unobstructed relatively narrow air passage at each side of the comb between the comb and 85 adjacent side wall of the nozzle whereby the suction will be concentrated at each side of the comb, said comb comprising spaced teeth projecting outward beyond the plane of the mouth opening and the bases of the spaces 90 between the teeth being located within the mouth of the nozzle and spaced inwardly from the said plane of the mouth opening, the said bases being beveled in opposite directions from a plane extending longitudinally through the center of the comb toward the sides of the comb, thereby forming a knife edge pointing toward the mouth of the nozzle. 95
